(57) **CLAIM**

The ornamental design for an elephant novelty, as shown and described.

DESCRIPTION

FIG. 1 is a left side elevational view of an elephant novelty, in accordance with the present invention.

FIG. 2 is a front view thereof;

FIG. 3 is a top view thereof;

FIG. 4; is a right side elevational view thereof;

FIG. 5 is a rear view thereof; and,

FIG. 6 is a bottom view thereof.

In the drawings, the broken line showing of ears and tail parts depicts environmental subject matter and form no part of the claim.
